John Rogers of New York, N.Y.
Letters Patent No. 1595 dated May 27-1862.

The schedule referred to in these Letters Patent and making part of the same.

To all whom it may concern, Be it known that I, John Rogers, of the City and State of New York, have invented or produced a new and original design for a group of Statuary, and I do hereby declare that the following is a full and exact description of the same.

The group is called The Checker Players, and consists of two figures A and B, seated on a bench D. Figure A, has his right foot C, on the ground E, his left leg F, rests on the seat of the bench D, with his right hand G, he points to his opponents checker on the board H, his left arm is thrown over the back of the bench D, and his left hand J, rests on the top of it. He has on a farmers frock K, he is in the action of laughing, with his head thrown back.

Figure B, is seated opposite figure A, on the bench D, his right leg I, is crooked under him, his right hand M, supports his chin N, his left hand O, is under his right elbow P, his spectacles Q, are placed over his forehead and he is looking at his chances on the checker board H.

Having thus described my invention, what I claim and desire to secure by Letters Patent, is a design for a group of Statuary as herein fully described and shown.
